2,569,603

COIN SELECTOR

John Gottfried, St. Louis, Mo.

Application August 29, 1945, Serial No. 613,302

4 Claims. (Cl. 194—97)

1

This invention relates to improvements in coin selectors, and more particularly, to means for segregating legitimate coins from counterfeit coins, slugs, discs, tokens and the like.

In the present invention, new and novel improvements in construction, hereinafter described, not only permit increased efficiency, but the apparatus combines features which may be confined in smaller space than heretofore found in conventional types of coin selectors.

It is an object of my invention to provide a coin rejector comprising in combination a coin cradle adapted to receive and be operated by coins of a predetermined weight and size, with means responsive to the movement of the cradle and coin for intercepting such coins when perforated.

It is a further object to provide means for preventing an undersize or underweight coin from operating or rocking the coin cradle.

The above and other features of novelty, advantages and capabilities will become apparent from the accompanying drawings and description of my invention. The construction shown and described, however, is to be understood as illustrative only, and not as defining the limits of my invention.

With my invention, inserted coins (which term as used herein includes legitimate as well as counterfeit coins, slugs, discs, washers, tokens and the like), while traveling through my device under the influence of gravity, are selected by size, physical characteristics, magnetic conductivity and resilience. It is not only adapted to differentiate between legitimate and spurious coins, but also to differentiate between undersized and oversized legitimate coins, and to directly return legitimate coins of incorrect denomination. Spurious coins of any given denomination for which the apparatus may be adapted, which may pass the test for size, if provided with a hole in the center, are intercepted by a pressure initiated, automatically returned finger which prevents further downward movement of said spurious coin.

Any rejected coin held at intermediate level will prevent downward movement of any other coin, legitimate or spurious, through the coin passageway until said spurious coin is ejected by novel scavenging means, hereinafter described.

The essential features of the improved coin selector apparatus embodying the present invention will be readily understood from a consideration of the appended claims when read in connection with the following specification and the accompanying drawings illustrating one embodiment of the invention, in which:

2

Figure 1 is a front elevation of the coin selector with the lower left hand portion broken away;

Figure 2 is a plan view of Figure 1 taken through section line 2—2;

Figure 3 is a broken away portion of Figure 1 with certain elements in their displaced positions;

Figure 4 is an end elevation of Figure 3 taken through section line 4—4;

Figure 5 is a broken away portion of Figure 1 with certain elements in further displaced positions;

Figure 6 is a broken away portion of Figure 1 with certain elements in further displaced positions;

Figure 7 is an enlarged perspective view of the wire finger and actuating lever for engaging coins with a hole in or near the center, the parts being shown in the positions assumed when a coin with a central hole is suspended by finger 18, lever 16 then being in a counterclockwise position;

Figure 8 is an enlarged perspective view of the wire finger shown in Figure 7, the arrows showing the direction of movement of said finger when a coin strikes arm 15 after leaving the cradle, the finger 18 being shown in a position assumed when lever 16 is between its extreme counterclockwise and clockwise positions;

Figure 9 is an enlarged perspective view of the wire finger in Figure 7 the finger 18 being shown in the position assumed when lever 16 is in a clockwise position, finger 18 then "feeling" the flat surface of a passing coin and in position to enter the hole of any coin with a central perforation; and

Figure 10 is a broken away portion of Figure 1 with certain elements in normal positions, and others in displaced positions.

Referring to Figure 1, the frame or main plate 1 is a support for all the elements of the coin selector. Pivotally mounted on the main plate 1 is a gate 2 provided with projecting lugs 3, by means of which the gate 2 swings on pintle 4. Pintle 4 is supported in lugs 5, which are fastened to main plate 1. The gate 2 is spaced from the main plate by lugs 50 (Fig. 2), which limit the inward swing of the free end of the gate. These lugs project from the plate 1 toward gate 2. Further, lugs 5 are spaced from the main flat body

portion of plate 1, as clearly shown in Fig. 2. The gate is resiliently held in position by a coil spring 6 (shown in Figure 2) mounted on pintle 7 and held in tension by washers 8.

In the operation of the coin selector, when a coin is inserted in the slot 9 formed by the out-

ward projection of the gate 2 at its upper left-hand corner, assuming that it is an acceptable legitimate coin of proper diameter and thickness, in falling downward, it will first contact the arm 15 (Figs. 10 and 3) and thereafter the counterweighted cradle 10, which is pivotally supported on the gate 2 at 11 and held in position by a cotter-pin 12. The cradle 10 is provided with projections 13 and 14 extending into the coin passageway through arcuate slots 21 and 33, respectively, cut into the gate 2. When an acceptable coin is inserted in the passageway 9, as shown in Figure 1, it drops by gravity and first strikes the arm 15 and thence bounces downwardly to a position impinging and resting upon projections 13 and 14 of the cradle. The weight of the coin in that position will cause the coin cradle 10 to rotate in a clockwise direction around pivot 11, if the coin is of sufficient diameter and weight. That is, the cradle turns from the position illustrated in Figs. 10 and 3, successively through the positions illustrated in Figs. 5 and 1 and finally to the position illustrated in Fig. 6. This movement will project the coin to the right, as shown by the dotted outline of said coin (Figure 5), thus causing said coin to contact arm 15, extending inwardly through a slot in the gate 2 from counterweighted lever 16, pivotally mounted on the gate 2 at 17. One function of arm 15 of lever 16 is to cause finger 18 (Fig. 4) to be moved out of the path of a coin which has turned the cradle, whereby the coin is permitted to start its fall past the finger. However, lever 16 is counterweighted, whereby after finger 18 is retracted from the space between gate 2 and plate 1 sufficiently to permit the coin to continue its progress, the finger is advanced again. The free end of the finger thus begins to "feel" a coin after the leading edge of the coin passes the finger. In short, lever 16 normally urges the finger into coin-obstructing position. The impact of a coin turning the cradle and pushing on arm 15 causes the finger to be withdrawn. As the coin presses against projection 15, it moves the lever 16 to its extreme clockwise (Figs. 6 and 9) position. This arm, during its travel, in turn lifts the latch or finger 18 (which is adapted to intercept perforated coins, hereinafter described), completely out of the path of said coin, permitting its passage downwardly to the magnetic and resilience tests, hereinafter described provided the coin, so "felt" by finger 18, does not have a central perforation.

Referring to Figure 3, when an undersized coin is inserted, its movement is shown by the dotted outlines. In its downward movement, it first contacts projection 15 of lever 16. Its impact against this projection causes it to bounce slightly to the left and thus pass between projections 13 and 14 without contacting either. The coin then drops directly downwardly until it contacts the inwardly projecting shelf 19 (shown in Figure 4) formed from main plate 1. Contact with shelf 19 causes the coin to be deflected into rejection passageway 20. This rejection passageway 20 may be arranged in the same manner as the rejection hopper shown in my U. S. Patent No. 2,326,214 or in any suitable manner well known to the art. An important function of the projection 15 on lever 16 is to prevent an undersize coin from hitting or striking projection 14 and rocking 70

As shown by Figure 5, when an oversize coin is inserted into entrance 9, it may be stopped between projection 13 on the cradle and projection 15 of the lever 16 which has moved pro-

jection 15 to the right to its extreme position, or if extremely oversize, it may be stopped between projection 13 and scavenger arm 26 shown in Figure 10. In either case, the oversize coin must be lifted from slot 9 or rejected by enlarging the space between plate 1 and gate 2. This is accomplished by the swinging action of the gate 2. This swinging action is effected by normal downward movement of the operating lever 22, shown in Figure 4, pivotally mounted at 23 and held in a horizontal normal position by a coil spring 24. Means for pivotally mounting an operating lever and holding it in normal position by spring-bias are well known to the art. A typical arrangement is shown in my U. S. Patent 2,326,214, for example. As the operating lever 22 is pressed downwardly, a twofold action is effected. Pin 25, attached to the lever 22 and projecting a slot in the plate 1, normally extends into a depression formed in gate 2. As the operating lever 22 and pin 25 move downwardly, pin 25 presses against the inside of gate 2, causing it to swing outwardly, thus enlarging the width of slot 9. In other words, the gate 2 is turned about pintle 4, in a counterclockwise direction (Fig. 2). Simultaneously with the aforesaid movement of pin 25, the downward movement of said pin also causes a clockwise (Fig. 3) turn of the scavenger wiper 26, as pin 25 strikes the lower edge of hole 27, offset from pivot 28. (The scavenger wiper is shown in normal position in Figure 1, and in both normal and scavenging positions in Figure 10.) The wiper 26 is pivotally mounted at 28 on plate 1. In the eccentric movement of pin 25 in hole 27 forcing the wiper 26 downwardly and to the left, any spurious coin with a hole in it, caught on the intercepting latch 18, or any coin failing to pass the magnetic test, hereinafter described, is deflected by the wiper 26 into rejection passageway 20 and away from the coin acceptance passage. The function of the wiper 26 is to knock any coin (in the space between gate 2 and plate 1) into the rejection pathway 20, as the gate 2 is opened. It will hereinafter be shown in detail how projection 29 of strip 30 causes any oversize coin stopped by projection 13 or any coin with a circular hole suspended on feeler 18 to be dropped into that space as the gate is opened.

Referring to Figure 6, when a spurious coin of the same diameter and weight as a legitimate coin, but with a hole or opening at or near the center, is inserted in slot 9, said coin, similar to the action of a legitimate coin, will fall between projections 13 and 14 of the cradle 10 and the clockwise rotation of the cradle 10 will project the coin laterally to the right until it contacts projection 15 of lever 16, thus moving lever 16 clockwise (Fig. 5). This movement of lever 16, which is linked with the finger or latch 18, as shown in Figure 7, causes the finger to move outwardly from plate 1, thus permitting the inner end of the finger 18 to ride on the surface of the coin until the instant that the hole passes under the end of finger 18. The finger 18 moves through the positions shown in Figs. 7 and 8 to that shown in Fig. 9, permitting the leading edge of the coin to pass the lower end of the finger, which lower end then presses against the flat surface of the coin as the counterweight on lever 16 urges the lever counterclockwise. The finger feels the flat surface of the coin until the hole in the coin registers with the finger. When a hole so registers, the parts assume the positions shown in Fig. 7. The weight of lever 16 then automatically forces the end of finger 18 through

the hole, intercepting further movement of the coin.

Any spurious coin thus held on finger 18 is removed when the scavenger operating lever 22 is depressed and gate 2 swings outwardly, as previously described, by contact with projection 29, the latter being an extension of the raised metal strip 30, held to gate 2 by means of flat spring 31 and screw 32 (shown in Figure 1). In order that the inwardly bent free end 29 of strip 30 may function to remove coins from finger 18, it is necessary so to arrange strip 30, with its body portion raised from the gate by element 28, that projection 29 remains stationary relative to plate 1 during the initial part of the outward swing of the gate. By reference to Figs. 1 and 6 it will be seen that as the gate 2 begins to swing outwardly any coin held by feeler 18 will be carried along until it contacts end 29 of strip 30, which contact causes the coin to be dropped into the space between gate 2 and plate 1, where it is scavenged and sent to the coin rejection pathway 20. After the coins have been knocked into that space, projection 29 may then move outwardly with the gate. Any suitable well-known expedient may be used for obtaining this action of projection 29. A prior-art expedient for performing this function is shown in U. S. Patent No. 2,292,628, for example.

As shown in Figures 8 and 9, the finger 18, which is linked to counterweighted lever 16, is held in position by a plate 34. The latter is provided with a grooved recess in its rear face in which the shaft of finger 18 is rotatably mounted and held in position when the plate 34 is fastened to the gate 2 by means of pin 35 and screw 36 (see Figures 3, 6 and 10). Figures 7 and 9 also show, respectively, the position of the intercepting finger 18 when holding a coin, and when the coin is being felt by feeler 18.

Referring to Figure 10, when a spurious coin which has passed all previous tests, such as diameter, thickness, weight and absence of any hole, it must then pass the magnetic test. This is provided by permanent magnets fastened to the front and rear faces of plate 1. Magnet 37 is fastened to the front face of plate 1 by screws and projects through swinging plate 2. Said magnet is shown in full in Figure 1. The opposing magnet 39, fastened to the rear of plate 1, is shown in Figure 2. The eddy currents set up by the magnets separate coin slugs having different electrical resistivities. When a spurious coin is stopped in the coin passageway by the action of these magnets, the passageway is cleared by the combined action of the outwardly swinging motion of gate 2 and scavenger wiper 26, initiated by depressing the operating lever 22, previously described.

In order to control the rolling motion of the coin as it enters into the magnetic field, the space between the wiper blade 26 and the coin runway 55 should be held fairly close. If a ferromagnetic slug of proper size were deposited in the unit, it would be arrested by the magnets. If the wiper blade 26 starts its downward swing at the moment the operating lever 22 is actuated, it would be possible to jam the coin between the coin runway and the wiper blade. To avoid this, the hole 27 in the wiper blade 26 is so arranged that when operating lever 22 starts its downward movement, the stud 25 on the operating lever will travel a predetermined distance before engaging with the lower part of the opening 27 in the wiper blade, setting up a timed de-

lay. This timed delay is sufficient to allow the gate to start swinging away from the main plate 1, thereby moving the coin runway out of the path of the slug, which will be wiped away from the magnetic field as the operating lever 22 is depressed all the way.

Any coin which passes the magnetic test, after having passed all prior tests, must pass the final test for resilience. As the coin passes the various tests previously described, it continues to fall downwardly to the right through the passageway between plate 1 and gate 2 until it strikes anvil 40, shown in Figure 1. If it has the proper resilience, it bounces to the left and passes into the legitimate acceptance passage. If not of the proper resilience, it drops into a reject passage. A suitable arrangement of coin rejection and coin acceptance pathways is shown in Fig. 5 of U. S. Patent No. 2,326,214, for example.

The gate 2, the strip 30 and the means for mounting the strip, the runway 55, the lugs 50, the spring 31, and the coin receiving, accepting, and rejecting pathways are known to the art, especially in view of the above-mentioned patents and are not per se claimed herein.

Having described my invention, I claim:

1. In a coin selecting apparatus of the character described, including a coin receiving pathway, a coin acceptance pathway and a coin rejection pathway; the combination of a pivotally mounted cradle having a pair of spaced projections normally extending into the coin receiving pathway and spaced apart to by-pass therebetween a coin having a diameter less than a coin of acceptable diameter and to engage a coin of acceptable diameter between said projections to divert said coin into the acceptance pathway, one of said projections being downwardly shiftable and adjacent the acceptance pathway; and a third projection independently mounted with respect to said cradle and normally projecting into both the coin receiving pathway and the coin acceptance pathway at a point adjacent to but above said downwardly shiftable projection of the pivoted cradle, whereby a coin moving along the coin receiving pathway will impinge said third projection prior to engaging the projections of the cradle, whereby the coin will be deflected and excessive velocity of the coin checked as it enters the cradle and will again impinge said third projection as it enters the acceptance pathway and as it tilts said cradle about its pivot due to its weight; said third projection being carried on the end of a weighted arm adapted for limited lateral movement with respect to the coin receiving pathway and said third projection being located in the path of movement of the coin during tilting of the cradle; together with a surface feeling finger normally in the coin acceptance pathway, and means responsive to the movement of the third projection to lift the surface feeling finger momentarily as the pivoted cradle places the coin in the acceptance pathway.

2. In a coin selecting apparatus of the character described, including a coin receiving pathway, a coin acceptance pathway and a coin rejection pathway; the combination of a pivotally mounted counterbalanced cradle having a pair of spaced projections comprising a downwardly shiftable projection on the side of the cradle adjacent the acceptance pathway and an upwardly shiftable projection on the opposite side thereof, with both of said projections normally extending into the coin receiving pathway and spaced apart

to bypass therebetween a coin having a diameter less than a coin of acceptable diameter and to engage a coin of acceptable diameter between said projections to divert said coin into the acceptance pathway; and a third projection independently mounted with respect to said cradle and normally projecting into the coin receiving pathway at a point adjacent to but above the downwardly shiftable projection of the pivoted cradle, whereby a coin moving along the coin receiving pathway will impinge said third projection prior to engaging the projections of the cradle, whereby the coin will be deflected to a position equally spaced between said projections as it enters the cradle so that the cradle will be tilted about its pivot by the weight of the coin rather than by the impact thereof; said third projection being carried on the end of a weighted arm adapted for limited lateral movement with respect to the coin receiving pathway and said third projection being located in the path of movement of the coin during tilting of said cradle.

3. In a coin selecting apparatus of the character described, including a coin receiving pathway, a coin acceptance pathway and a coin rejecting pathway; the combination of a pivotally mounted counterbalanced cradle having a pair of spaced projections comprising a downwardly shiftable projection on the side of the cradle adjacent the acceptance pathway and an upwardly shiftable projection on the opposite side thereof, with both of said projections normally extending into the coin receiving pathway and spaced apart to bypass therebetween a coin having a diameter less than a coin of acceptable diameter and to engage a coin of acceptable diameter between said projections to divert said coin into the acceptance pathway; and a third projection independently and pivotally mounted with respect to said cradle and normally projecting into the coin receiving pathway at a point adjacent to but above the downwardly shiftable projection of the pivoted cradle, whereby a coin moving along the coin receiving pathway will impinge said third projection prior to engaging the projections of the cradle, whereby the coin will be deflected to a position equally spaced between said projections as it enters the cradle so that the cradle will be tilted about its pivot by the weight of the coin rather than by the impact thereof, said third projection being positioned with relation to said downwardly shiftable projection so that the third projection engages the coin for a period during tilting of the cradle.

4. In a coin selecting apparatus of the character described, including a coin receiving pathway, a coin acceptance pathway and a coin rejection pathway; the combination of a pivotally mounted cradle having a pair of spaced projections normally extending into the coin receiving pathway and spaced apart to bypass therebetween a coin having a diameter less than a coin of acceptable diameter and to engage a coin of acceptable diameter between said projections to divert said coin into the acceptance pathway, one of said projections being downwardly shiftable and adjacent the acceptance pathway; and a third projection independently mounted with respect to said cradle and normally projecting into both the coin receiving pathway and the coin acceptance pathway at a point adjacent to but above said downwardly shiftable projection of the pivoted cradle; whereby a coin moving along the coin receiving pathway will impinge said third projection prior to engaging the projections of the cradle, whereby the coin will be deflected and excessive velocity of the coin checked as it enters the cradle and will again impinge said third projection as it enters the acceptance pathway and as it tilts said cradle about its pivot due to its weight, said third projection being located in the path of movement of the coin during tilting of the cradle; together with a surface feeling finger normally in the coin acceptance pathway, and means responsive to the movement of the third projection to lift the surface feeling finger momentarily as the pivoted cradle places the coin in the acceptance pathway.
